Primary Examiner — Paul D Bohannon(74) *Attorney, Agent, or Firm* — Faegre Drinker Biddle & Reath LLP(57) **CLAIM**

The ornamental design for a chair as shown and described.

DESCRIPTION

FIG. 1 is a top perspective view of a chair according to the invention.

FIG. 2 is a bottom perspective view of the chair of FIG. 1.

FIG. 3 is a front view of the chair of FIG. 1.

FIG. 4 is a rear view of the chair of FIG. 1.

FIG. 5 is a right side view of the chair of FIG. 1.

FIG. 6 is a left side view of the chair of FIG. 1.

FIG. 7 is a top view of the chair of FIG. 1.

FIG. 8 is a bottom view of the chair of FIG. 1.

FIG. 9 is an enlarged top perspective view of one of the front legs of the chair of FIG. 1, the other front leg being a mirror image; and,

FIG. 10 is an enlarged bottom perspective view of one of the front legs of the chair of FIG. 1, the other front leg being a mirror image.

The dashed broken lines show portions of the article that form no part of the claimed design. The dot-dot-dash broken lines depict boundaries of the enlarged views and form no part of the claimed design.
